(57) **CLAIM**

The ornamental design for a drying poncho, as shown and described.

DESCRIPTION

FIG. 1 is a plan view of a drying poncho showing my new design, in a fully opened position;

FIG. 2 is a side elevational front view thereof in a folded position of the front side thereof, the opposite rear side being a mirror image thereof;

FIG. 3 is a plan view of the folded poncho shown in FIG. 2;

FIG. 4 is one end view of the folded poncho shown in FIG. 2, the opposite end being a mirror image thereof;

FIG. 5 is a bottom view of the folded poncho shown in FIG. 2; and,

FIG. 6 is a perspective view thereof as it would normally appear when worn.
